UNITED STATES PATENT OFFICE.

EMIL F. GENNERT, OF NEW YORK, N. Y.

DESIGN FOR A PRISMATIC GLASS CONE FOR OIL-BURNERS.

No. 40,014.

Specification for Design.

Patented May 25, 1909.

Application filed May 4, 1908. Serial No. 430,872. Term of patent 14 years.

To all whom it may concern:

Be it known that I, EMIL F. GENNERT, a citizen of the United States, residing in the city, county, and State of New York, have invented a new, original, and ornamental Design for Prismatic Glass Cones for Oil-Burners, of which the following is a specification, reference being had to the accompanying drawing, forming part thereof.

Figure 1 is a front view, Fig. 2 is a side view and Fig. 3 is an inverted plan view of a prismatic glass cone, showing my new design.

The cone has internally flattened converging and diverging faces, thus forming parallel prisms.

I claim—

The ornamental design for a prismatic glass cone for oil burners as shown and described.

EMIL F. GENNERT.
